PLASTIC COATED FABRIC

Thomas H. Doherty, South Bend, Ind., assignor to United States Rubber Company, New York, N.Y., a corporation of New Jersey

Filed Apr. 12, 1962, Ser. No. 69,683

Term of patent 14 years

(Cl. D87—3)

The FIGURE is a plan view of a plastic coated fabric, showing my new design. A design unit is shown within the dot and dash lines. This unit is repeated in regular succession as indicated by the extensions beyond the unit boundaries.

I claim:

The ornamental design for a plastic coated fabric, as shown and described.
